CLAIM

The ornamental design for a camera bezel, as shown and described.

DESCRIPTION

FIG. 1 is a top and back perspective view of the camera bezel shown in an environment of use with the broken lines representing a truck that forms no part of the claim.

FIG. 2 is a top view of a camera bezel;

FIG. 3 is a side view from the left side of FIG. 2;

FIG. 4 is a bottom view thereof;

FIG. 5 is a top front perspective view thereof; and,

FIG. 6 is a bottom front perspective view thereof.
